**COMBINED DRIP PAN AND CONTAINER
FOR LIQUIDS**

Andrew R. Lewis, 9166 E. 4th, Tulsa, Okla. 74112

Filed Mar. 19, 1970, Ser. No. 21,980

Term of patent 3½ years

Int. Cl. D9—07

U.S. Cl. D9—175

FIG. 1 is a perspective view of a combined drip pan and container for liquids showing my new design;

FIG. 2 is a top plan view;

FIG. 3 is a bottom plan view;

FIG. 4 is a sectional view taken on the line 4—4 of FIG. 2;

FIG. 5 is an elevational view showing the long side not shown in FIG. 1; and

FIG. 6 is an elevational view looking from the left of FIG. 5.

I claim:

The ornamental design for a combined drip pan and container for liquids, as shown.
